UNITED STATES PATENT OFFICE.

HYMAN DWORKIS, OF CHICAGO, ILLINOIS.

DESIGN FOR A CEDAR CHEST.

Application filed February 20, 1929. Serial No. 30,148. Term of patent 7 years.

To all whom it may concern:

Be it known that I, HYMAN DWORKIS, a citizen of Russia, residing at Chicago, in the county of Cook and State of Illinois, have invented a new, original, and ornamental Design for Cedar Chests, of which the following is a specification, reference being had to the accompanying drawing forming part thereof, in which,

The figure is a perspective view of a cedar chest showing my new design.

I claim:

The ornamental design for a cedar chest, as shown.

In witness whereof I affix my signature.

HYMAN DWORKIS.
